(57) **CLAIM**

The ornamental design for a light diffuser, as shown and described.

DESCRIPTION

FIG. 1 is a top perspective of a light diffuser showing the new design;

FIG. 2 is a bottom perspective view thereof;

FIG. 3 is a top plan view thereof;

FIG. 4 is a bottom plan view thereof;

FIG. 5 is a side elevation view thereof;

FIG. 6 is an opposite side elevation view thereof;

FIG. 7 is a front elevation view thereof;

FIG. 8 is an enlarged view along line 8 shown in FIG. 1;

FIG. 9 is an enlarged view along line 9 shown in FIG. 2;

FIG. 10 is an enlarged view along line 10 shown in FIG. 3; FIG. 11 is an enlarged view along line 11 shown in FIG. 4; and,

FIG. 12 is an enlarged view along line 12 shown in FIG. 6. The dash-dot broken lines depict the boundaries of the enlarged views and form no part thereof.

The portions of the light diffuser shown in evenly spaced dash-dot broken lines illustrate portions of the light diffuser that form no part of the claimed design.
